UNITED STATES PATENT OFFICE.

HERBERT L. ADAMS, OF SOMERVILLE, MASSACHUSETTS.

LIFE-PRESERVER FOR AVIATORS.

1,194,691.

Specification of Letters Patent. Patented Aug. 15, 1916.

Application filed May 31, 1912. Serial No. 700,827.

To all whom it may concern:

Be it known that I, HERBERT L. ADAMS, citizen of the United States, residing at Somerville, in the county of Middlesex and 5 State of Massachusetts, have invented certain new and useful Improvements in Life-Preservers for Aviators, of which the following is a specification.

My invention relates to an improved life 10 preserver for use by aviators in the event of accident.

The object of my invention is to provide means for disposing conveniently and releasing quickly, when desired, an improved 15 parachute to enable aviators to save their lives in case of accident.

A further object is to provide a parachute with scoops on the outer edge to force air into said parachute which will cause said 20 parachute to open, take air and fill quickly, so that an accident near the ground may not prove fatal to the aviator. And a still further object is to provide a parachute which is so constructed or so connected to the body 25 of the aviator, that the direction in which it is moving may be controlled to some extent.

To these ends my invention consists in certain novel features, which I will now proceed to describe and will then particularly 30 point out in the claims.

In the accompanying drawings Figure 1 is an elevation of my improved life preserver in use. Fig. 2 is an elevation of the same showing the life preserver normally 35 disposed about the body of the aviator. Fig. 3 is an elevation of a parachute showing valves for steering. Fig. 4 is an elevation of a parachute showing the reinforcing device. Fig. 5 is an elevation showing 40 a controlling valve; Fig. 6 is a vertical section on the line 6—6 of Fig. 5; Fig. 7 is a detail in perspective showing one of the air gathering scoops; Fig. 8 is a perspective view of the body harness showing the connection of the various controlling lines therewith, and Fig. 9 is a sectional detail showing 45 the means for connecting a ring to the body harness.

Referring more particularly to the separate parts of the device: 1 indicates a jacket or other supporting device.

2 are reinforcing strips which pass under the arm pits and return to the ring 3, which is on top of each shoulder or other convenient place. These two strips are held together by straps 4.

The hooks 5 may be of any convenient pattern, or the ropes 6 may be made permanently fast to the ring 3.

In order that the parachute 7 may open 60 quickly, a scoop or scoops 8 or other means may be placed at the lower edge of parachute 7. The scoops 8 are to have means 11 to keep them open and also to have a rope 12, or other means to keep the scoops 8 in 65 the position required. The upper end 13 of said scoop 8 is to open inside of the parachute 7. The rings 3, with the connecting ropes 6, are also so far apart that they divide the strain on the parachute 7 into two 70 parts, and this aids largely in causing the folds of the parachute 7 to separate quickly as well as giving means to change the direction of the flight to the ground by movement of the shoulders.

The ropes 6 are in such a position that they can be moved by the hand to change the forward or backward movement. Therefore the parachute may be used as a glider in selecting a favorable spot on which to 75 land.

To aid in steering, the parachute may have valves in it and may be made in any convenient way, of which the way shown is one. The parachute has openings 23 85 which are covered by flaps 14. Each flap is held fast at 15 to the parachute and passes through a slit 16 in the latter, said slit being located below the opening 23. On the lower free end of the flap is an eyelet 17 to 90 which a rope 18 is connected, the same passing through a guide loop 19 located adjacent to the bottom edge of the parachute. The ropes 18 extend down to the members 2 of the body harness and are connected thereto by hooks 20 or other suitable means. The ropes 12 connected to the scoops 8 also extend down to the body harness, so as to be within reach of the operator, and they may be connected to the harness by hooks 20^a. 95

The parachute, when not in use, reposes in a sack or pocket 9 carried by the aviator as shown in Figs. 1 and 2.

Fig. 4 shows means for reinforcing a parachute made of some very light material 105 with material to increase the strength of said light material. The reinforcement consists of circumferential and radial bands, the circumferential bands extending in a spiral form around the parachute. The circumferential bands are shown at 21, and the radial bands at 22. The same result may be 110

obtained by weaving the parachute in such a way or with such material that a greater amount of strength may be had with less weight than if material was uniform in all respects.

5 While I have embodied in the foregoing the main features of my invention, I do not wish to be limited to the specific details thereof, but desire to be protected in various 10 changes, alterations, and modifications, which may come up within the scope of the appended claims.

Having thus described my invention what I claim as new and desire to secure by Letters Patent is—

1. A parachute having a series of circumferential and radial reinforcing bands applied thereto, the circumferential bands extending in a spiral form around the 20 chute.

2. The combination with a parachute having air escape openings at different points, valves for said openings, and independent operating means connected to said valves.

25 3. The combination with a parachute, of air gathering scoops mounted on the outer edge of the parachute and opening to the under surface thereof.

4. The combination with a parachute, of air gathering scoops mounted on the outer 30 edge of the parachute and opening to the under surface thereof, and means for holding the air inlet ends of the scoops distended.

5. The combination with a parachute, of 35 a body harness to which the parachute is connected, air gathering scoops mounted on the outer edge of the parachute and opening into the under surface thereof, and a controlling line connected to each scoop and 40 extending to the body harness.

50 6. The combination with a parachute, of ing air escape openings at different points, flaps adapted to cover said openings, said flaps being fastened to the parachute above 45 the openings, and the parachute below the openings having slits through which the free ends of the flaps are adapted to pass, and controlling lines connected to the free ends of the flaps.

In testimony whereof I have affixed my signature in presence of two witnesses.

HERBERT L. ADAMS.
